UNITED STATES PATENT OFFICE.

HARRY A. DOUGLAS, OF BRONSON, MICHIGAN, ASSIGNOR TO DOUGLAS & RUDD MFG. CO.,
OF BRONSON, MICHIGAN, A CORPORATION OF MICHIGAN.

REFLECTING ELECTRIC LAMP.

1,261,787.

Specification of Letters Patent Patented Apr. 9, 1918.

Application filed February 19, 1917. Serial No. 149,666.

To all whom it may concern:

Be it known that I, HARRY A. DOUGLAS, citizen of the United States, residing at Bronson, in the county of Branch and State 5 of Michigan, have invented a certain new and useful Improvement in Reflecting Electric Lamps, of which the following is a full, clear, concise, and exact description.

My invention relates to reflecting electric 10 lamps and has for its object the provision of improved mechanism whereby the lamps may be switched into and out of circuit and other mechanism whose operation is permitted by the switching mechanism for adjusting the lamp bulb with reference to the concave reflector that enters into the lamp construction.

In accordance with one of the features of 20 my invention there are employed switching contacts within the reflector carrying concave casing that is preferably but not necessarily distinct from the reflector, a plug in the shell that holds the lamp bulb and coupled with the shell in a manner that permits 25 the plug to be turned, a rod extending from the plug to the casing and operable from the exterior of the casing to turn the plug, a head piece connected with the rod for turning it and a spring for maintaining the head 30 piece in engagement with the casing whereby the head piece is confined to a single plane of rotation.

In accordance with another characteristic 35 of the invention the shell that carries the lamp bulb is movable in and out whereby the lamp bulb may be adjusted with respect to the reflector and in order that this adjustment may be permitted the rod is movable longitudinally and with respect to the head 40 piece while remaining coupled with the head piece whereby the head piece is adapted to turn the rod in all of the positions to which the shell and lamp bulb may be adjusted in and out. The mechanism for adjusting the 45 shell in and out is desirably inclusive of a screw connected with the shell and operable from the exterior of and engaged with the casing.

I will explain my invention more fully by 50 reference to the accompanying drawing showing the preferred embodiment thereof and in which Figure 1 is a side elevation, partially in section, of a reflecting lamp containing features of my invention; Fig. 2 is 55 a longitudinal view, partially in section and

partially in elevation of portions of the structure illustrated in Fig. 1; Fig. 3 illustrates a part of the adjusting rod and the head therefor in perspective; Fig. 4 is a view on line 4—4 of Fig. 1; Fig. 5 is a view partially in elevation and partially in section of parts; and Fig. 6 is a view taken on line 6—6 of Fig. 2.

Like parts are indicated by similar characters of reference throughout the different 65 figures.

The concave reflector 1 is received in the reflector carrying concave casing 2 here shown as distinct and spaced apart from the reflector, but to which construction the invention is not to be limited. When these elements 1 and 2 are separate they are coupled in any suitable way, leaving a space intervening between the reflector and casing. The reflector includes a rearwardly extending 70 tubular continuation 3 in fixed relation with the balance of the reflector, this continuation constituting a holder or mounting. A spring tongue 4 is integrally formed with 75 a shell 5 that constitutes a holder for contact carriers, this spring tongue having ample clearance at its side margins to permit it freely to function. Some part of the tongue, such as the rear free end thereof, has a part 6 projecting therefrom which is nar- 80 rrower than the balance of the tongue and is slightly narrower than a slot 7 in the holder 85 3 whereby this portion may project into the slot to prevent the shell from turning with respect to the slot while at the same time the side margins of the tongue 4 are adapted to press against the side margins of the slot 7. The tongue thus presses upon a surface of 90 the holder 3 and, where there is but one tongue, forces the shell toward the opposite 95 side of the holder whereby the shell is held in engagement with the holder 3. The slot 7 is elongated so that the shell 5 may be moved back and forth in its holder 3 whereby in the structure illustrated the position 100 of the lamp bulb 8 which is carried by the forward end of the shell in front of the reflector may be adjusted with respect to the reflector. The base 9 of the lamp bulb 8 constitutes the forward contact carrier and 105 as the arrangement illustrated this contact carrier 9 carries two rear contacts 10 and 11. The lamp base or contact carrier 9 is provided with bayonet pins 12 engageable within bayonet 110

seats 13 constituting parts of bayonet slots 14. The rear contact carrying plug 15 within the casing 2 is provided with terminal blocks 16 having binding screws 17 by which 5 circuit wires may be secured to the terminal blocks. These terminal blocks are cylindrical and the forward ends thereof are tubular, springs 18 being included in the tubular portions of the terminal blocks and 10 operating to press contacts 19, 20 forwardly into engagement with the contacts 10 and 11, all of these contacts being within the casing. The springs 18 and the contacts 19 and 20 thus not only serve to establish circuit for 15 the lamp but also operate to hold the lamp base 9 in bayonet pin and slot connection with the shell 5. The plug 15 is rotatable within the rear end of the shell 5 in order that it may perform its switching function 20 and when thus movably mounted it is provided with bayonet pins 21 and which are receivable in alternate bayonet seats 22, 23, the plug being inserted from the front end of the shell with its pins passing along the 25 bayonet slots 14 until they are in the zone that includes the bayonet seats 22, 23 whereafter the base of the lamp bulb is inserted in the shell with its pins 12 placed in the bayonet seats 13. The springs 18 thus not 30 only serve to hold the bayonet pins 12 in the seats but also serve to hold the bayonet pins 21 in the seats to which they are adjusted.

It will be observed that the complementary switching contacts 10 and 19 are eccentric 35 with respect to the shell as are also the complementary switching contacts 11 and 20 so that as the plug is turned these contacts are either brought into engagement or are separated according to the direction of movement 40 of the switching plug 15. When the lamp is in open circuit the contacts 19 and 20 are pressed against the insulating portions of the lamp base that are adjacent the contacts 10 and 11, the springs 18 continuing to press the contacts 19 and 20 forwardly to maintain the bayonet pins upon the switching plug and upon the lamp base in their respective bayonet seats. The shell 45 and the parts within it are in front of the casing 2 and in order that the switching plug 15 may be turned or otherwise moved with respect to the lamp base to cut the lamp in and out of circuit I employ a motion transmitting connection in the form of a 50 switching rod 24 which is connected at its inner end with the switching plug and which is operable from the exterior of the casing. This switching rod may be turned to turn the switching plug to its open circuit or closed circuit 55 position, this arrangement being broadly claimed in my co-pending application, Serial No. 149,666, filed February 19, 1917. Other features are claimed in my co-pending application Serial No. 149,664, filed 60 February 19, 1917. In my present invention

the head piece 25 for the rod 24 is held in engagement with the casing by means of the spring 26 whose outer end engages the head piece and whose inner end engages the plug 15. The spring thus confines the head 70 piece to a single plane of rotation. The rod is movable longitudinally with respect to the head piece but turns therewith, the back end of the rod being desirably made square as indicated at 24¹ while the head piece is provided with a correspondingly shaped bore 25¹ receiving the square end of the shaft 24. 75 The shell 5 carries a bracket 27 that projects through the slot 28 in the holder 3. A screw 29, supplied in addition to the rod 24, 80 is in threaded connection with the bracket 27 and is therefore connected with the shell 5. The head 30 of the screw 29 engages the casing. By turning the screw the shell 5 is moved in and out to adjust the lamp bulb 85 with respect to the reflector. The spring 26 expands or contracts to follow, at its forward end, the plug 15, this movement of the plug being permitted when the screw is turned owing to the engagement between 90 the rod 24 and the head piece 25 that permits this rod to move in and out with respect to said head piece. This screw and its complementary parts thus constitute means supplied in addition to the rod 24 for moving 95 the lamp bulb in and out.

The particular form of lamp 11 illustrated is what is known as a "spot light" but to which form of lamp the invention is not to be limited. When the lamp is in the form 100 of a "spot light" the casing is provided with a handle 21 and this handle I constitute a rearward continuation of the casing, the switching rod 24 passing through the handle to a point where it is operable from the 105 exterior of the casing.

Any suitable means may be employed for establishing circuit relation between the contacts upon the plug 15 and the external source of current, there being illustrated a 110 well known form of connector 15¹ which may be employed for this purpose.

While I have herein shown and particularly described the preferred embodiment of my invention I do not wish to be limited to 115 the precise details of construction shown as changes may readily be made without departing from the spirit of my invention, but having thus described my invention I claim as new and desire to secure by Letters Patent the following:—

1. In a reflecting electric lamp, the combination with a reflector carrying casing; of an electric lamp bulb; a shell carrying the lamp bulb at its front end and having bayonet pin and slot connection with the base of the lamp bulb; eccentrically disposed switching contacts within the casing for cutting the lamp in and out of circuit; a plug within the casing and mounted to turn in the 120 125 130

- shell to have alternative positions to cut the lamp in and out of circuit and having bayonet pin and slot engagement with the shell in the alternative positions of the 5 plug; a rod extending from said plug and operable from the exterior of the casing for turning the plug; spring means for holding said contact in engagement to establish circuit and operating to hold the plug in circuit opening and circuit closing positions; a head piece for the rod; a spring for maintaining the head piece in engagement with the casing, said rod being movable longitudinally and with respect to the head piece and turning with the head piece in its various 10 positions with respect thereto; and a screw in connection with the shell and engaging the casing and operable to move the shell and lamp bulb in and out.
- 20 2. In a reflecting electric lamp, the combination with a reflector carrying casing; of an electric lamp bulb; a shell carrying the lamp bulb at its front end; a contact carrying plug within the casing and coupled with the shell for supplying current to the lamp and mounted to turn with respect to the shell to cut the lamp in and out of circuit, there being engageable eccentrically located switching contacts in the lamp circuit, one 25 upon the plug; a motion transmitting rod extending from the plug and operable from the exterior of the casing to turn said plug; a head piece for the rod; a spring for maintaining the head piece in engagement with the casing, said rod being movable longitudinally and with respect to the head piece and turning with the head piece in its various 30 positions with respect thereto; and a screw in connection with the shell and engaging the casing and operable to move the shell and lamp bulb in and out.
- 35 3. In a reflecting electric lamp, the combination with a reflector carrying casing; of an electric lamp bulb; a shell carrying the lamp bulb at its front end and having bayonet pin and slot connection with the base of the lamp bulb; eccentrically disposed switching contacts within the casing for cutting the lamp in and out of circuit; a plug 40 within the casing and mounted to turn in the shell to have alternative positions to cut the lamp in and out of circuit and having bayonet pin and slot engagement with the shell in the alternative positions of the plug; a rod 45 extending from said plug and operable from the exterior of the casing for turning the plug; spring means for holding said contacts in engagement to establish circuit and operating to hold the plug in circuit opening and circuit closing positions; a head 50 piece for the rod, said rod being movable longitudinally and with respect to the head piece and turning with the head piece in its various 55 positions with respect thereto; and a screw in connection with the shell and engaging the casing and operable to move the shell and lamp bulb in and out.
- 60 4. In a reflecting electric lamp, the combination with a reflector carrying casing; of an electric lamp bulb; a shell carrying the lamp bulb at its front end; a contact carrying plug within the casing and coupled with the shell for supplying current to the lamp and mounted to turn with respect to the shell to cut the lamp in and out of circuit, there being engageable eccentrically located switching contacts in the lamp circuit, one upon the plug; a motion transmitting rod extending from the plug and operable from the exterior of the casing to turn said 65 plug; a head piece for the rod, said rod being movable longitudinally and with respect to the head piece and turning with the head piece in its various 70 positions with respect thereto; and a screw in connection with the shell and engaging the casing and operable to move the shell and lamp bulb in and out.
- 75 5. In a reflecting electric lamp, the combination with a reflector carrying casing; of an electric lamp bulb; a shell carrying the lamp bulb at its front end; switching contacts within the casing for cutting the lamp in and out of circuit; a plug within the casing and coupled with the shell and carrying one of said contacts and movable with respect to the shell; means operable from the exterior of the casing for effecting relative motion between the plug and shell to cut the lamp in and out of circuit; and a screw engaging the casing and being connected with the shell and being operable from the exterior of the casing to move the shell in and out to adjust the lamp bulb with respect to the reflector.
- 80 6. In a reflecting electric lamp, the combination with a reflector carrying casing; of an electric lamp bulb; a shell carrying the lamp bulb at its front end; engageable eccentrically disposed switching contacts within the casing for cutting the lamp in and out of circuit; a plug within the casing and mounted to turn in the shell and coupled therewith and carrying one of said contacts; means operable from the exterior of the casing for turning the plug to cut the lamp in and out of circuit; and a screw engaging the casing and being connected with the shell and being operable from the exterior of the casing to move the shell in and out to adjust the lamp bulb with respect to the reflector.
- 85 7. In witness whereof, I hereunto subscribe my name this 27th day of January, A. D., 1917.

HARRY A. DOUGLAS.
